UNITED STATES PATENT OFFICE.

JOHN GOOD, OF BROOKLYN, NEW YORK.

MACHINE FOR SPREADING AND DRAWING HEMP, &c.

SPECIFICATION forming part of Letters Patent No. 328,582, dated October 20, 1885.

Application filed January 10, 1885. Serial No. 152,474. (No model.)

To all whom it may concern:

Be it known that I, JOHN GOOD, a citizen of the United States, residing in the city of Brooklyn, county of Kings, and State of New 5 York, have invented a new and useful Improvement in Machines for Spreading and Drawing Hemp, Flax, and other Fibrous Materials, of which the following is a specification, reference being had to the accompanying 10 drawings.

This invention relates to that class of spreading and drawing machinery in which the fiber is operated upon by means of catenary series of gill-pins.

15 The objects of this invention are to increase the capacity and efficiency of such machinery, to save much of the room occupied by the machines as now constructed and organized, and to reduce the labor required to attend to 20 them.

The invention consists, principally, in the combination of two independently working catenary series of gill-pins so geared to run in opposite directions that the operative pins 25 of the two series move toward each other, and interposed drawing-heads and delivery apparatus, whereby the fibers operated upon by the two series of gill-pins are drawn in opposite directions, and collected together and delivered 30 in the form of a single sliver.

The invention further consists in improvements, hereinafter fully described and claimed, relating to the drawing-heads and delivery apparatus employed in the combination hereinbefore mentioned.

As introductory to a detailed description of my invention, I will state, generally, that a machine embodying my invention resembles two drawing-frames or two spreaders from 40 which the delivery-rollers and funnel-like condensers had been removed, placed end to end with their drawing-heads close together, and having between them a delivery apparatus by which the fibers received from the drawing-heads of the two machines are collected 45 together and delivered as a single sliver.

In the accompanying drawings, Figure 1 is a side elevation of a drawing-frame embodying my invention. Fig. 2 is a central longitudinal section of the same. Fig. 3 is a transverse vertical section of the same between the

two drawing-heads and through the center of the delivery apparatus. Fig. 4 is a diagram representing a longitudinal view of the principal working parts of a spreader embodying 55 the principal feature of my invention.

Similar letters of reference indicate corresponding parts in the several figures.

A, Figs. 1, 2, 3, designates the main framing of the machine. B B' and C C' are the 60 wheels which support the chains of the two catenary series D D' of gill-pins, the wheels B B' being the drivers of the chains. E E' are the feed-rolls, and F F' are the feed-boards, over which the slivers or sticks to be drawn 65 pass to the feed-rolls. G G' are the drawing-heads.

All the parts hereinabove referred to, except the drawing-heads, may be and are represented as such as are now to be found in drawing-frames in common use. The drawing-heads may be of any suitable kind, but those represented are the subject of my United States Patent No. 315,766, dated April 14, 1885, and are particularly well adapted to the 75 carrying out of the present invention.

Each of these drawing-heads consists, principally, of two drawing-rolls, a b, the upper one, b, of which is covered with elastic vulcanized india-rubber, and an endless belt, c, 80 of leather running on the roll b and on an upper extension-roll, d. Pressure-springs e are adjustably applied to the journal-boxes of the rolls b, and adjusting-screws h are applied to the journal-boxes of the upper rolls, d, to adjust the belts c to a proper tension. The drawing-heads are so arranged that their two belts, c c, run parallel, or nearly so, and close together, as shown in Figs. 1 and 2, and they are so geared and driven that the contiguous 90 parts of the two belts run upward. The journal-boxes of the extension-rolls d are arranged in small frames f, which are adjustable by screws g in the standards H H, which are erected on the main frame A to support the 95 drawing-heads. The adjusting-screws h are also fitted to these frames f. The horizontal adjustment thus provided for the rolls d enables the upper parts of the belts c c to be brought as near together as desirable.

Above the belts c c there are arranged in suitable bearings a pair of delivery-rolls, J J,

the axes of which are transverse to the axes of the rolls of the drawing-heads, and between the said belts and the said delivery-rolls is a funnel-shaped condenser, *i*. (See Fig. 3.) On 5 one side of the delivery-rolls is an inclined delivery board or conductor, *I*.

One of the lower drawing-rolls *a* is represented as made to constitute the main shaft of the machine, being furnished on one side of 10 the machine with a pulley, *j*, (shown in dotted outline in Figs. 1 and 2,) to receive motion from a belt, *k*. The gearing through which the other parts of the machine receive motion is all on the other side of the machine, which 15 is the side presented to view in Fig. 1. The two rolls *a a* are geared together by spur-gears *l l*. On the shaft of the first roll *a*, on which is the driving-pulley, there is secured a pinion, *m*, which gears with a spur-wheel, *n*, 20 through which motion is given to the driving-wheels *B B'* of the endless chains of the two catenary series of gill-pins. This wheel *n* turns freely on a fixed stud, *o*, secured on the framing *A*, and there is secured to the said 25 wheel *n* a pinion, *p*, which gears directly into a spur-wheel, *q*, on the shaft of the driving-wheel *B* of the catenary series of pins *D*. The said pinion *p* is also geared through an intermediate spur-wheel, *p'*, with a spur-wheel, *q'*, 30 on the shaft of the driving-wheel *B'* of the other series of pins. This gearing is such that the operative pins of each of the two catenary series—that is to say, those pins which are at any time presented upward—will run toward 35 the operative pins of the other series, those of each series running toward the drawing-heads, which, it will be observed, come together at the center of the machine.

The feed-rolls *E E'* derive motion from the 40 chains of their respective series of pins through gearing *r s t* and *r' s' t'*, as shown in Fig. 1.

The upper drawing-rolls, *b*, may be geared each to its respective lower one, *a*, by spur-gears; but they are represented as not geared, 45 the belts *c* and the upper drawing-rolls being driven by the surfaces of the lower drawing-roll acting on the belts through the slivers passing between them.

The delivery-rolls are driven by a band, *u*, 50 running from a pulley, *v*, on the shaft of one of the lower drawing-rolls *a* to a pulley, *w*, on the lower delivery-roll, the band being guided by idler-pulleys *u' u''*, as shown in Figs. 1 and 2.

55 The operation of this machine is as follows: Any number of slivers or sticks—say from one to twelve—may be taken from as many cans arranged at each end of the machine, and passed over the feed-boards *F* and *F'* to 60 the feed-rolls *E E'*, from which the slivers pass to the two catenary series of pins, *D D'*, and thence between the drawing-rolls *a* and belts *c* of the two drawing-heads. The fibers from each pair of feed-rolls are acted upon 65 independently by the respective catenary series of gill-pins and drawing-rolls in the same

way as the fibers are acted upon in an ordinary drawing-frame. The fibers from both series of pins, after being thus independently drawn by the drawing-rolls and pins, are all carried upward together between the two endless belts *c c*, and pass together through the condenser *i*, in which they are brought together in the form of a single sliver, which is taken by the delivery-rolls *J J*, and thereby delivered into the conductor *I*, whence they may go to a can or any other suitable receptacle. 70

The embodiment of my invention in a drawing-frame having now been fully described, a brief reference to the diagram, Fig. 4, will be 80 sufficient to explain its application to a spreader. This diagram shows the principal parts of a spreader, in each half of which the system or combination of two catenary series of gill-pins is the same as that which is the 85 subject of my United States Letters Patent No. 311,310, dated January 27, 1885. This spreader embodies the principal parts of two spreaders having such a system of chains as is described in said Letters Patent in the same 90 way that the drawing-frame shown in Figs. 1, 2, and 3 embodies the principal parts of two drawing-frames with an interposed delivery apparatus common to both.

What I claim as my invention, and desire 95 to secure by Letters Patent, is—

1. The combination of two catenary series of gill-pins, two interposed drawing-heads, one set of delivery-rolls common to both series of gill-pins and both drawing-heads, and 100 gearing and driving mechanism, substantially as herein described, whereby said series of gill-pins and drawing-heads are caused to run in opposite directions and toward each other, and the delivery-rolls are caused to deliver in 105 a single sliver all the fibers received by the two drawing-heads from the two series of chains, substantially as herein described.

2. The combination of two catenary series of gill-pins, two drawing-heads interposed between said series, one set of delivery-rolls common to both of said drawing-heads, a condenser common to both drawing-heads interposed between said heads and delivery-rolls, and gearing and driving mechanism, substantially as herein described, for driving the said 110 series of gill-pins and drawing-heads in opposite directions and driving said delivery-rolls, substantially as and for the purpose herein set forth. 115

3. The combination of two catenary series of gill-pins, two interposed drawing-heads, each comprising two drawing-rolls, an extension-roll, and an endless belt running on one of said drawing-rolls and on the extension-roll, the two endless belts being parallel and near together, and mechanism, substantially as herein described, for driving said series of pins in opposite directions and for driving the said rolls to cause the contiguous parts of 125 said belts to run in the same direction, as and for the purpose herein set forth. 130

4. The combination, with the two catenary series of gill-pins and two interposed drawing-heads, each comprising two drawing-rolls, an extension-roll, and an endless belt running on one of said drawing-rolls, and on the extension-roll driving mechanism for driving the said pins and rolls, and means, substan-

tially as herein described, of adjusting said belts as near together as may be desirable, as herein set forth.

JOHN GOOD.
